UNITED STATES PATENT OFFICE.

HENRY L. BLODGETT, OF CHICAGO, ILLINOIS, ASSIGNOR TO THE GOFORTH
WINDOW COMPANY, OF SAME PLACE.

SASH-CORD FASTENER.

SPECIFICATION forming part of Letters Patent No. 293,554, dated February 12, 1884.

Application filed January 23, 1883. (No model.)

To all whom it may concern:

Be it known that I, HENRY L. BLODGETT, residing at Chicago, in the county of Cook and State of Illinois, and a citizen of the United States, have invented new and useful Improvements in Sash-Cord Fasteners, of which the following is a full description, reference being had to the accompanying drawings, in which—

10 Figure 1 is a front elevation of parts of an upper and lower window-sash; Fig. 2, a side elevation of the same parts; Figs. 3 and 4, side views of the cord-fastener detached and enlarged; Fig. 5, a top view of the fastener; Fig. 15 6, a bottom view, and Fig. 7 a vertical section of the lower end.

The object of this invention is to improve the sash-cord fastener patented to W. Goforth August 8, 1882, by giving the fastener a more 20 secure hold on or attachment to the sash, and to combine therewith a sash-lock; and its nature consists in the several combinations and improvement of parts hereinafter set forth and claimed as new.

25 In the drawings, A, B indicate the upper and lower sash; C, the cord-tubes; D, the top plate; E, notch; F, side arm; G, the cord; H, the fastening-pin; a, vertical slit; b, cross-slit; c, notch in the under edge of the slit b; 30 d, projecting lip or incline on the arm F; e, notch or stop in the lip d; f, connecting-pin; g, contraction or shoulder in the tube c; h, a tapering or wedge-shaped screw for wedging the end of the cord within the tube under the 35 shoulder in the latter.

The tube C in its general construction is similar to that shown in the patent referred to—that is to say, it is a complete tube at its lower end and a partial tube at its upper end—40 a sufficient portion being cut away to permit the cord to pass into or out of it, and the plate D may have the notch of the corresponding plate in said patent or not.

The plate D is provided with a side arm, F, 45 which is of sufficient length to reach the sash B, as shown in Fig. 2. The end of this arm is turned up or otherwise made so as to form or have an inclined projection, d, fitted to pass under a projecting pin, f, on the sash B. This 50 incline is provided with a notch or stop, e, to hold the arm F in its proper position.

The pin f may be a smooth pin or a headed screw. The head-screw will serve to prevent any separation between the sashes A and B when they are locked, while the smooth pin 55 will require a less correct fitting. It will of course be understood that this pin is not to project so far as to prevent the passage of either sash past the other, and that, therefore, when the sashes are in exact line with each other, it 60 will be necessary to set this pin in a small recess formed for that purpose. Usually such a recess will not be required, as the ordinary offset is sufficient to allow the sash to pass freely.

The lower end of the tube C is provided with 65 two slits, a, b, in the form usually known as "bayonet-joints" or "catches." The horizontal portion b of these catches are provided with notches c, which hold the tube C in place when the strain of the sash-weight is upon the cord G, 70 and it aids in forming a lock for the arm F, as it prevents the easy rotation of the plate D, and the horizontal portions b are made of a length sufficient to prevent the unfastening of the tube in turning the arm F to lock or unlock the sashes, and to prevent an undue turning of the plate D a limit-stop may be applied to the sash. A coupling-pin, H, is driven in or run through the sash, as shown in Fig. 2, in such position that the notches a, b of the 75 tube C will engage with said pin and thereby hold the tube C firmly in place, and the notch c will prevent it from getting out as long as there is any strain on the cord. By taking the strain of the cord off by hand or otherwise, 80 the tube C can be rotated and drawn without difficulty, as it is not necessary to have it fit so tight as to make its rotation difficult. The placing of the pin H down in the sash gives it 85 a strong hold, so that heavy glazed sash may be securely held without danger of pulling the tube out, as is the case when they are only held by a single wood-screw at the top. The application of this catch to the tube C makes it necessary to free the lower end of the tube 90 from the cord. To accomplish this purpose of getting the cord out of the way and give it a firm fastening, I provide the interior of the tube with an annular shoulder, g, which the end of the cord passes, and then insert a common wood-screw, h, which securely attaches the end of the cord to the tube by wedging the 95 100

end of the cord within the tube under the shoulder *g*.

The operation of this improved device will be readily understood from its description, and it will also be understood that for the upper sash the plate D and its attachment will be omitted, and that when the plate D and arm F are both applied to each side of the lower sash the arms F must be made right and left.

10. What I claim as new, and desire to secure by Letters Patent, is as follows:

1. The combination, with the sashes A and B, of the horizontal rotating plate D, having the laterally-projecting sidearms, F, provided with the vertical projection *d* for engaging the pin on the sash, substantially as described.

2. The combination of the cord-tube C, having the bayonet-joint *a b*, with the coupling-pin H of the sash, all constructed and operating substantially as specified.

3. The cord-tube C, constructed with the interior annular shoulder, *g*, in combination with the cord G and the tapering screw *h*, passing into the cord and wedging the same within the tube under the said shoulder, substantially as described.

HENRY L. BLODGETT.
